UNITED STATES PATENT OFFICE.

RICHARD BÜRK, OF SCHWENNINGEN, WÜRTEMBERG, GERMANY, ASSIGNOR
TO MATHEW MICOLINO, OF NEW YORK, N. Y.

LOCKING-LATCH.

SPECIFICATION forming part of Letters Patent No. 258,986, dated June 6, 1882.

Application filed January 21, 1882. (Model.)

To all whom it may concern:

Be it known that I, RICHARD BÜRK, of Schwenningen, Oberamt Rottweil, Würtemberg, in the Empire of Germany, have invented 5 certain new and useful Improvements in Door-locks, of which the following is a specification.

This invention relates to that class of door-locks in which the bolt operated by the knob is also used for locking purposes, so as to obviate the necessity for a separate lock and latch; and the invention consists of a guided and sprung-actuated main bolt operated in the usual manner by a double cam on the tubular knob-spindle, which cam engages a central projection on the bolt, in combination with a second cam, which is applied to an axially-turning bolt in the spindle and thrown into line with a second projection on the main bolt by means of a key that is inserted into a key-hole in the knob and adapted to engage the interior bolt of the spindle. The inner socket-shaped end of the sliding main bolt carries a fixed semi-cylindrical shank, against which may be thrown a similar shank carried by an axially-turning latch, so as to lock the main bolt when thrown into line with the shank at the rear end of the same. 15

In the accompanying drawings, Figures 1, 2, and 3 represent inside views of my improved 30 door-lock with the bolt in different positions, parts being broken away so as to show the different operating mechanisms. Fig. 4 is a vertical transverse section of the lock on line xx , Fig. 3, and Fig. 5 is an end view of the knob.

Similar letters of reference indicate corresponding parts.

In the drawings, A represents the casing of my improved door-lock, and B the bolt of the same, which projects with its beveled front end 40 through the face-plate of the lock-casing, the opposite end, B^2 , of the bolt being made socket-shaped for the reception of a strong spiral spring, E, by which the bolt is thrown to the outside of the casing for closing the door. The 45 end portions of the bolt B are connected by arc-shaped intermediate pieces, B' , which pass around the spindle of the knobs. The open middle portion of the bolt B B^2 between the pieces B' has, in line with the bolt B B^2 , 50 inwardly-extending projections a and d . The

projection a at the rear part of the bolt is acted upon by a double cam, b , keyed to the hollow knob-spindle C, for the purpose of opening the bolt in whatever direction the inner or outer knob, C' , may be turned. The face of 55 the projection d is made concave, so as to be adapted to closely hug or ride the spindle C when withdrawing the bolt, but which is engaged by a segmental cam, D, keyed to a solid bolt, D' , at the interior of the spindle C. The 60 tubular spindle C is made of two sections, of which the outer section carries at its inner end, within the casing, a disk, b' , while the inner section carries the double cam b . The disk b' and cam b are rigidly connected by screw-bolts 65 b^2 , as shown clearly in Fig. 4. The double cam b is recessed at its inner face, so as to provide between it and the disk b' a space of sufficient size for the turning of the cam D of the bolt D' . The bolt D' and cam D are turned by means 70 of a key, D^2 , which is inserted through a key-hole of the inner or outer door-knob, and which engages either end of bolt D' , as shown clearly in Fig. 4. By turning the bolt D' by the key the cam D is thrown into line with the projection d of the bolt B, as shown in Fig. 3, a spring-catch, e , of the interior bolt, D' , being thrown into socket-hole e' of the spindle C, and thus the main bolt B locked by the cam D. The locking-cam D may be thrown back clear 75 of the projection d from the outside or inside by means of the key D^2 whenever the door is desired to be opened.

In connection with the lock is also used a night-latch, E' , which is turned around its axis 85 by a button at its outer end, the latch E' being arranged in line with and back of the rear end, B^2 , of the main bolt B. The latch E' is provided with a semi-cylindrical inwardly-projecting shank, f , which engages a similar shank, 90 f' , at the inside of the socket-shaped end portion B^2 of the bolt B whenever the button of the latch E' is turned so that the shank f is in line with the shank f' . In this case the opening of the lock from the outside is prevented. As in this improved lock the functions of the common locking-bolt operated by the knob-spindle are combined directly with a locking mechanism and a night-latch, it can be manufactured cheaper than the locks at pres- 95 100

ent in use, requires less time for being applied to the door, and is operated with greater convenience, as a small key can be used therewith.

Having thus described my invention, I claim—

5 as new and desire to secure by Letters Patent—
1. As an improvement in door-locks, the combination of a tubular spindle, C, having a recessed double cam, b, and an interior axially-turning bolt, D', having a cam, D, and also 10 extending through the recessed double cam b, with a guided and spring-actuated main bolt, B, having arc-shaped middle pieces, B', and inwardly-extending projections a and d, which 15 projections are engaged either by the double cam b or by cam D, according as the bolt is to be withdrawn or locked, substantially as specified.

2. As an improvement in door-locks, the combination of the guided and spring-actuated 20 main bolt B, having a socket-shaped rear part, B², and an interior semicircular shank, f', with an axially-turning latch, E', having a semi-

circular shank, f, whereby the main bolt is locked when the shanks are thrown into line with each other, substantially as specified. 25

3. As an improvement in door-locks, the combination of a recessed double cam, an interior axially-turning bolt having a cam and extending through said recessed cam, and a guided and spring-actuated main bolt having 30 arc-shaped middle pieces, inwardly-extending projections, socket-shaped rear part, and an interior semicircular shank, with an axially-turning latch having a semicircular shank adapted to lock the main bolt, substantially as 35 described.

In testimony that I claim the foregoing as my invention I have signed my name in presence of two subscribing witnesses.

RICHARD BÜRK.
